UNITED STATES PATENT OFFICE.

GEORGE C. BLICKENSDERFER, OF STAMFORD, CONNECTICUT.

TABULATOR MECHANISM.

1,116,553.

Specification of Letters Patent. Patented Nov. 10, 1914.

Application filed November 11, 1908. Serial No. 482,114.

To all whom it may concern:

Be it known that I, George C. Blickensderfer, a citizen of the United States, residing at Stamford, county of Fairfield, and 5 State of Connecticut, have invented certain new and useful Improvements in Tabulator Mechanism, fully described and represented in the following specification and the accompanying drawings, forming a part of the 10 same.

This invention relates to certain improvements in tabulator mechanisms for typewriting machines.

The invention has for its object to produce an improved tabulator mechanism for typewriting machines so constructed and having the keys so marked that the operator may readily write numbers in columns with the figures of the same numerical place arranged in vertical lines, and write these figures either solid or in separated groups, as may be desired, and without making any change or adjustment in the tabulator mechanism.

25 Referring to the drawings which illustrate one embodiment of the invention, Figure 1 represents in side elevation a typewriting machine having the improved tabulator mechanism thereon. Fig. 2 is a front elevation of the machine shown in Fig. 2. Fig. 3 is a plan view of the tabulator mechanism. Fig. 4 is a sectional side elevation of the construction shown in Fig. 3, with one of the tabulator levers in operative position. Fig. 5 is a detail sectional view. Figs. 6 and 7 illustrate two kinds of work which may be written on the machine illustrated.

While the tabulator mechanism which 40 forms the subject of the invention may be applied to machines varying in construction, it is shown as applied to a wheel machine of the well-known Blickensderfer type.

45 Referring to the particular machine illustrated in the drawings, 1 indicates the frame, 2 the type wheel, 3 the platen roll, 4 the keyboard, and 5 the space bar; all of which parts are or may be of the usual and accepted construction in this class of machines.

While the tabulator mechanism which forms the subject of the invention may be constructed as to its details in various ways, it will include a series of stops which, in 50 the particular construction illustrated, are formed by a series of stopping levers 6, these

levers being actuated by keys 7 which may be conveniently formed integral with the levers. While the stopping levers, when this form of stop is employed, may be supported in various ways, in the particular machine illustrated, there is provided a bracket 8. The attaching means may be of any desired form, but as shown comprise a screw 9 and dowel pins 10. As illustrated, 55 the bracket 8 is provided with what may be termed a comb 11. This comb may be conveniently formed by casting a projection as the bracket and milling out the slots which form the interstices between the teeth of the 70 comb. The teeth of the comb, in the particular construction shown, are perforated laterally and through these perforations extends a pivot screw 12. As shown, each of the tabulator levers is perforated, and each 75 of them is supported on the screw and lies between the consecutive teeth of the comb. To increase the rigidity of the levers and to enable them to be made light, the outer end of the bracket 8 may be upturned, as at 13, so and slots may be milled through this outer upturned projection so as to form a second comb between the teeth of which the outer ends of the levers lie. If desired, a bar 14 85 may be secured across the top of the upturned milled end 13 of the bracket which bar overlies the levers where they pass through the second comb.

As usual, in tabulator constructions, the scale of the machine, indicated at 15, will be provided with one or more movable column stops, the number of these stops used varying according to the number of columns of numbers being written. The stops may be of any suitable construction. In the construction illustrated, one stop is shown, and it consists of a block 16 recessed to receive the bar 15, the stops being locked to the bar by a thumbpiece 17 pivoted to the block at 18. If desired, the scale may be provided 95 with a series of teeth, as shown at 19, and the thumbpiece may have an engaging projection at 20 which enters between two of the teeth 19 so as to hold the block rigidly on the scale and prevent it from slipping when the 105 carriage is stopped. The operative portion of the stop is marked 21. The machine may be provided with the usual lever, indicated at 22, for turning the platen roll and simultaneously therewith release the feed, so that 110 the carriage may be shifted.

In tabulator mechanism embodying the

invention the stops will usually be operated by or from keys and these keys will be provided with different systems of markings, so that the stops may be actuated to cause 5 members to be written in different arrangements and without any adjustment or change of the tabulator mechanism.

The particular tabulator attachment illustrated is provided with 12 stop levers, and 10 certain of the keys of these tabulator levers are provided, as illustrated with two systems of markings, so that the operator simply by following these markings may write the 15 figures of columns of numbers either solid or 20 in separate groups. The different characters of work which this tabulator is thus 25 capacitated to produce are illustrated in Figs. 6 and 7. Assuming, for instance, that the operator desires to write the number 30 678 67, he strikes the key marked \$100, raising the lever into the path of the carriage stop. The carriage is now moved forward until the operative face 21 of the stop comes in contact with the lever. The carriage is 35 now stopped in the proper position, so that when the type keys bearing the numbers 6, 40 7, 8 are depressed, the spacer operated and the 6 and 7 type keys operated, the final right hand figure of the number comes in the 45 proper column and the remaining figures also are brought in the proper columns. If the operator desires to write the number 54 628 678 74, he depresses the key marked 50 \$10 M, and the carriage is advanced as before until the stop on the scale strikes the 55 end of the lever. The carriage is now in the proper position, so that the several figures and the intervening spaces and the final right hand figure will be brought in the 60 proper columns underneath the preceding number. Assuming, however, that the operator desires to write the figures solid, as for statistical work, as, for instance, 789, he depresses the key of the tabulator bearing 65 the number "3." The carriage will be stopped in the proper position, so that when the figures are printed, the final right hand figure will be in its proper column. If the operator desires to write the number 678987, 70 he operates the key "6." This will stop the carriage in the proper position, so that the number may be printed solid bringing the figures of the various denominations in their proper columns. It will be seen from these 75 concrete examples of the work of the particular machine illustrated, when work with the figures arranged in groups is desired, which will most frequently be when commercial work expressing sums of money is 80 to be written, the operation of the tabulator key corresponding to the highest numerical place of the amount to be written will cause

the carriage to stop in such position with regard to the final figure as to allow the number to be written in denominational 85 groups including where desired, a decimal group. If, on the other hand, it is desired to write the same combination of figures solid, the key of the tabulator bearing the 90 mark or figure corresponding to the numerical place which the first figure of the number is to occupy, is depressed. This stops the carriage in the proper position, so as to permit the number to be printed solid and yet bring the various figures of the 95 number in their proper columns. In other words, it will be seen that by operating the proper keys of the tabulator shown, some of the figures to the left of the unit figure will be placed at different distances, or at a 100 different number of spaces, from the unit figure, according to whether it is desired to write the numbers solid or in separated groups. For example, if the combination of figures 678 67 is to be written in separated groups to present dollars and cents, thus, 678.67, the carriage will be stopped so as to bring the first figure 6 in the sixth space from the final figure. If, however, it is desired to write this combination of figures solid, thus 67867, then by the depression of the "5" key of the tabulator, the first figure 6 will be written in the fifth place from the final figure.

Changes and variations may be made in the construction and markings by which the invention is carried into effect. The invention is not, therefore, to be limited to the specific construction and markings shown.

What is claimed is:—

1. In a tabulator mechanism, a plurality of keys arranged in columns and in rows; a set of indices for said columns arranged to constitute an arithmetical series; and a set of indices for certain of said rows arranged to constitute a geometrical series.

2. In a tabulator mechanism, a plurality of keys arranged in columns and in rows; a set of indices for said columns arranged to constitute an arithmetical series, there being one character of this series on each key; a set of indices for certain of said rows arranged to constitute a predetermined geometrical series; and certain keys in said lateral rows not bearing characters of said geometrical series, as specified.

In testimony whereof, I have hereunto set my hand, in the presence of two subscribing witnesses.

GEORGE C. BLICKENSDERFER.
